[57] CLAIM

The ornamental design for an angled electrical connector housing, as shown and described.

DESCRIPTION

FIG. 1 is a perspective view of an angled electrical connector housing according to my new design;

FIG. 2 is a top, front angled view of the angled electrical connector housing of my new design shown in FIG. 1;

FIG. 3 is a bottom plan view of the angled electrical connector housing of my new design shown in FIGS. 1 and 2;

FIG. 4 is a top plan view of the angled electrical connector housing of my new design shown in FIGS. 1-3;

FIG. 5 is a left side elevational view of the angled electrical connector housing of my new design shown in FIGS. 1-4; and,

FIG. 6 is a right side elevational view of the angled electrical connector housing of my new design shown in FIGS. 1-5. The broken line showing of environment in FIGS. 1 and 3-6 is for illustrative purposes only and forms no part of the claimed design. The angled electrical connector of the claimed design can be either an inlet (male connector) or a receptacle (female connector).
